VENTILATED WALL

Filed Sept. 13, 1949

UNITED STATES PATENT OFFICE

2,645,824

VENTILATED WALL

Edwin J. Titsworth, Goodrich, Mich.

Application September 13, 1949, Serial No. 115,475

1 Claim. (Cl. 20—4)

1 This invention relates to the art of building, and more particularly to a molding for use with an insulated wall of a building.

The object of the invention is to provide a molding which is adapted to be attached to an insulated wall of a building whereby moisture-laden air can pass through the molding so that the moisture will not damage the paint on the outside of the building.

Another object of the invention is to provide an insulated wall construction for a building, the wall construction including siding that is spaced from an insulated panel member, the molding of the present invention being perforated and communicating with the space between the siding and the panel member, whereby moisture-laden air can pass from this space to the outside so that this moisture will not damage the paint on the outside of the building.

A further object of the invention is to provide a molding which is extremely simple and inexpensive to manufacture.

Other objects and advantages will be apparent during the course of the following description.

In the accompanying drawings forming a part of this application, and in which like numerals are used to designate like parts throughout the same;

Figure 1 is a vertical transverse sectional view taken through the insulated wall, with the molding of the present invention attached thereto;

Figure 2 is an enlarged vertical sectional view taken through one of the molding members;

Figure 3 is a fragmentary bottom plan view of the molding member of Figure 2;

Figure 4 is a fragmentary perspective view of one of the molding members.

Referring in detail to the drawings, there is shown a portion of a building which includes a roof 10, the building including the usual side panels or inside boards 11. A layer of insulation 12 is arranged contiguous to the outer surface of the side panel 11, Figure 1.

The building further is provided with a concrete footing 13 that supports the sill 14, there being floor boards 15 extending along the bottom of the building. Suitable joists 16 are supported on the sill 14.

The building construction further includes a sheathing 17 that has shingles or siding 18 secured to the outer surface thereof. The sheathing 17 is spaced from the layer of insulation 12, and the space defined between the sheathing 17 and the insulation 12 is indicated by the numeral 19.

2

The present invention is directed to a molding member whereby moisture-laden air can pass out from the space 19 so that the moisture therein will not damage the paint on the shingles 18. Thus, by providing a ventilation or escape means for the moisture, the moisture will not pass through the sheathing 17 and shingles 18 to cause the paint to work loose from the shingles 18.

10 In actual use, both the upper and lower ends of the siding 17 have projecting therefrom the molding members which are designated by the numeral 20. Each of the molding members 20 includes a body portion, and the body portion comprises a top section 21 and a bottom section 22 which is arranged in spaced parallel relation below the top section 21. The molding member 20 is preferably fabricated of a rust-resistant material, such as aluminum or other metal or the molding member can be made of any suitable material. The ends of the top and bottom sections 21 and 22 are connected together by an arcuate section 23, Figures 2 and 4. Extending from the top section 21 and secured thereto, or formed integrally therewith, is a flange or lip 24, while extending from the bottom section 22 is a similar flange or lip 25. The bottom section 22 is provided with a plurality of perforations or openings 26 therein, so that the moisture-laden air can pass from the space 19 through the openings 26 and to the outside.

15 From the foregoing, it is apparent that a molding member has been provided for use with an insulated wall construction. The siding 17 and the shingles 18 are cut away adjacent the top and bottom, as shown in Figure 1, and the molding members 20 of the present invention are projected through the cut-away portions of the sheathing and shingles. The lips 24 and 25 engage the inner surface of the sheathing 17 to prevent the molding members 20 from accidentally working loose from the wall construction. Then, moisture-laden air which accumulates in the space 19 will travel in the direction of the arrows and this moisture-laden air will pass from the space 19 through the openings 26 where it will be dissipated to the outside. Thus, this moisture in the insulation space 19 will not be absorbed or worked through the siding 17 and shingles 18, so that the moisture will not cause the paint on the outside of the building to work loose.

20 I claim:

25 In a building construction the combination with a panel member, a layer of insulation ar-

ranged contiguous to the outer surface of said panel member, and a sheathing spaced from said insulation to define a space therebetween, of a pair of moulding members each having a portion thereof arranged exteriorly of said sheathing and extending horizontally along the outer face of the sheathing, said moulding members being arranged adjacent the top and bottom of said sheathing and supported by the latter, said moulding members each comprising a top section extending downwardly and outwardly and arranged angularly with respect to said panel member, a bottom section arranged in spaced parallel relation below said top section, an arcuate section connecting said top and bottom sections together, there being a plurality of spaced openings arranged in said bottom section for the egress therethrough of moisture laden air, a first flange extending from said top section, and a second flange arranged in alignment with said first flange and extending from said bottom section, said openings being arranged contiguous to

said arcuate section, said moulding members being secured to the sheathing and communicating with each other through the space defined between the sheathing and the insulation.

EDWIN J. TITSWORTH.
